FURNACE

Elmer H. Berryman, San Francisco, and Henry K. Huppert, Millbrae Highlands, Calif., assignors to American Electric Company of California, San Francisco, Calif., a corporation of California

Application October 18, 1933, Serial No. 694,102

5 Claims. (Cl. 219—35)

This invention relates to electric furnaces and in particular to electric muffles such as used in dentistry.

For economy of operation a muffle should be 5 only large enough to accommodate the material being heated, but inasmuch as a dentist or other technician finds it necessary to make castings, burn out wax matrices and bake porcelain objects which vary to a considerable extent in 10 size, either a large furnace must be used or a number of furnaces of different sizes. For obvious reasons the latter alternative is prohibitive for the majority of operators.

Furthermore for some purposes high temperatures are required and for others it is essential 15 that low temperatures be used. For example in making porcelain castings a low temperature oven is first used to set the material and then a high temperature oven is used for baking and glazing the casting. After this has been done the casting should be gradually cooled 20 without chilling to properly anneal the material and consequently the low temperature furnace must again be resorted to.

25 One of the objects of our invention is the provision of a multiple muffle having a set of resistance elements in common which can be used as a rheostat for either muffle by connecting it in series with the individual resistance elements of each muffle as desired.

Another object of our invention is the provision 30 of a muffle having a set of resistance elements a portion of which may be used as a rheostat for controlling the heat generated within the muffle.

Still a further object of our invention is the provision of a multiple furnace comprising a 35 pair of nested muffles, one being a high temperature muffle and the other a low temperature muffle.

The invention possesses other advantageous features, some of which with the foregoing, will be set forth at length in the following description, where we shall outline in full that form of our invention which we have selected for illustration in the drawings accompanying and forming a part of the present specification. In said drawings, we have shown one form of our invention, but it is to be understood that we do not 45 limit ourselves to such a form, since the invention as set forth in the claims, may be embodied in a plurality of forms.

Referring to the drawings:

Figure 1 is an isometric drawing of the assembled muffle.

Figure 2 is a vertical midsection taken longitudinally of the furnace.

Figure 3 is a wiring diagram of the multiple furnace as shown in Figure 2.

Figure 4 is a wiring diagram of a modified furnace wherein a single muffle is used and in which a part of the resistance element serves as a rheostat for controlling the temperature within the muffle.

As clearly shown in Figures 1 and 2 the furnace 10 comprises a base 1 on which is mounted a low temperature muffle 2. Within the muffle 2 is a second substantially smaller muffle 3 capable 15 of operating at high temperatures. The interior side walls of both muffles are provided with grooves or channels 4 and 5 within which the resistance elements of the muffles are accommodated. As shown in Figure 2 the base 6 of the muffle 2 is slightly spaced from the base 1 of the furnace in order to form a slot 7 within 20 which a rheostat control bar 8 is adapted to operate. The central part of the control bar 8 is pivoted on the pin 9 secured to the base 1 and its inner end is adapted to register with any one of the spaced contact points 11 through 20, 25 as diagrammatically shown in Figure 3. To the outer end of the control bar 8 is secured a knob 21 of insulating material and the base 1 is provided with spaced reference marks 22 arranged in an arc and corresponding to the contact points 30 11 through 20. By placing the control bar 8 in registration with any one of the reference marks 22 the opposite end of the control bar will contact one of the corresponding contact points 11 through 20.

35 Disposed within the grooves or channels 4 provided in the inner walls of the muffle 2 are two sets of resistance elements. As shown in Figure 3 one set consists of resistance elements 31 through 41 connected in series and which may conveniently be located in the upper portion of the muffle 2. In effect all of these elements form a single resistance, and since the muffle 2 is designed to be operated at low temperatures (-1400° F.) these resistance elements may be 45 made of a base metal wire such as nichrome. The other set consists of resistance elements 42 through 50 connected in series and preferably located in the lower portion of the muffle 2. Each of the elements 42 through 50 is connected as 50 shown in Figure 3 with the contact points 11 through 20. By rotating the control bar 8 any one of the contact points 11 to 20 can be connected with the line or source of current and consequently the resistance elements 42 through 55

50 may be made to serve as a rheostat. Disposed within the small high temperature muffle 3 is a resistance element 51 one end of which is secured to the lower end of the resistance element 31, 5 while the other end is connected to the upper terminal 52 of a double throw switch 53. The element 51 should be designed to operate at a temperature 2450° F. or higher and therefore may be made of platinum wire. The lower end of the element 40 connects with the opposite terminal 54 of the switch 53 while the switch 53 connects with the upper end of the element 41. The lower end of the element 31 connects through a switch 55 with the remaining leg of the line, thereby 15 completing the circuit. By closing the switch 55 and the switch 53 against the terminal 52 the rheostat formed by the elements 42 through 50 may be placed in series with the resistance element 51 of the small muffle 3, and the temperature adjusted by cutting in as many of the resistance elements 42 through 50 as is desired. By closing the switch 53 against the terminal 54 the rheostat may be placed in series with the resistance element 31 through 40, located in the upper 25 portion of the large muffle 2. It is to be particularly noted that the floor of the muffle 2 also serves as a floor for the muffle 3, and that the resistance elements forming the rheostat are located in this floor common to both muffles. In 30 either position of the switch 53 the current must of necessity flow through the rheostat, and consequently heat the floor of both muffles. If therefore it is desired to make a small casting the switch 53 may be closed against the terminal 52 35 in which case the small muffle is heated while the large muffle is inactive, but nevertheless serves as additional insulation. If it is desired to make a large casting the switch 53 is closed against the terminal 54 whereby the large muffle 2 is heated and the small muffle 3 is inactive. In this 40 case the casting may be placed either on top of the small muffle or immediately in front of it on the common floor. As shown in Figures 1 and 2 the furnace may be provided with a pyrometer if 45 desired.

Furthermore it will be seen that this arrangement of muffles can be used very effectively for two purposes. The upper portion 2 being a low heat muffle serves as a preliminary drying chamber 50 and the lower portion 3 as a high heat finishing chamber or muffle.

While the upper muffle heats to the desired temperature the lower muffle is automatically heated by means of conducted heat without the use of its 55 heating elements being operative thereby saving time and electrical power.

After completing a high heat baking or fusing process in the lower muffle the work is transferred to the upper muffle for annealing. The temperature 60 of the upper muffle is high enough for this purpose because some of the original heat is conserved within its well insulated outer walls and also from the conducted heat of the lower muffle.

It should also be noted that in transferring the 65 casting, porcelain jacket crowns or other dental work from one muffle to the other there is no necessity of taking it out of the furnace and subjecting it to the outside atmospheric temperature, and consequently it is not chilled and strains are 70 prevented.

In Figure 4 we have shown a wiring diagram for a furnace in which a single muffle is utilized. In this modification there are two sets of resistance elements, one set consists of resistance element 61 through 69, while the other set 5 consists of resistance element 71 through 81, and as clearly shown the elements of one set are disposed intermediate the elements of the other set. Each of the elements 61 through 69 are connected with the spaced contact points 82 through 10 101. The control bar 102 connects through the switch 103 with one leg of the line, while the other leg of the line connects with the left hand end of the element 81. Contact 101 connects both with the left hand end of the resistance element 15 69 as well as with the right hand end of the resistance element 71. It will therefore be noted that by closing the switch 103 and placing the control bar 102 in contact with contact 101 the current is made to pass successively through resistance element 71 through 81 and that by rotating the control bar 102 to the left any desired 20 number of elements 61 through 69 may be placed in series with the elements 71 through 81.

It will therefore be seen that we have provided 25 a furnace comprising a pair of muffles so associated that they supplement each other as to temperature as well as to capacity or size.

We claim:

1. An electric furnace comprising a pair of 30 muffles of substantially different sizes, one contained within the other and having a wall in common heated by a set of resistance elements which function as a rheostat for either muffle.
2. An electric furnace comprising a pair of 35 muffles having a wall in common; heating elements disposed within each muffle; a set of resistance elements disposed within said common wall forming a rheostat and a switch for connecting said rheostat in series with the heating 40 element of either muffle.
3. An electric furnace comprising: a muffle; a second substantially smaller muffle disposed within said first muffle; a set of resistance elements within said first muffle forming a rheostat; 45 a heating element within said second muffle; a heating element within said first muffle and a switch for connecting said rheostat in series either with the heating element in the second muffle or with the heating element in said first muffle. 50
4. An electric furnace comprising a base; a muffle mounted on said base; a second substantially smaller muffle formed within said first muffle; a heating element disposed within said first muffle; a heating element disposed within 55 said second muffle; a rheostat disposed within one of said muffles and a switch for connecting said rheostat in series with either of said heating elements.
5. A furnace comprising a pair of nested 60 muffles having a wall in common; a high temperature heating element associated with one of said muffles; a low temperature heating element associated with the other of said muffles; a rheostat associated with said common wall and a 65 switch for connecting said rheostat in series with either of said heating elements as desired.
